Primary Examiner — Elizabeth A. Albert(74) *Attorney, Agent, or Firm* — Richards Patent Law
P.C.(57) **CLAIM**

The ornamental design for a pen, as shown and described.

DESCRIPTION

FIG. 1 is a perspective view of a pen showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines on the top in FIG. 6 are included to show a portion of the pen that forms no part of the claimed design.
